REFRIGERATION

Erik Sigfrid Lynger, Stockholm, Sweden, assignor,
by mesne assignments, to Servel, Inc., New
York, N. Y., a corporation of Delaware

Application June 22, 1938, Serial No. 215,111
In Germany July 6, 1937

28 Claims. (Cl. 62—125)

This invention relates to refrigeration, and it is an object of the invention to provide an improvement for transferring heat whereby cooling may be effected at one or a plurality of places at a higher level than a source of refrigeration.

The above and other objects and advantages of the invention will become apparent from the following description taken in conjunction with the accompanying drawings forming a part of this specification, and of which:

Fig. 1 is a view more or less diagrammatically illustrating a refrigeration system together with a heat transfer system embodying the invention;

Fig. 2 is an enlarged view, partly in section, illustrating more clearly the heat transfer system shown in Fig. 1;

Fig. 3 is a fragmentary view diagrammatically illustrating a modification of the invention shown in Figs. 1 and 2;

Fig. 4 is a view more or less diagrammatically illustrating another modification of the invention.

Fig. 5 is a view diagrammatically illustrating a further modification of the invention and in which a plurality of places of cooling are provided at a higher level than a source of refrigeration; and

Fig. 6 is a fragmentary view illustrating a still further modification of the invention having a plurality of places of cooling at a higher level than a source of refrigeration.

In Fig. 1 the invention is shown in connection with a refrigeration system of a uniform pressure absorption type. Such a system includes a generator 10, condenser 11, evaporator or cooling element 12, and an absorber 13 which are interconnected in a manner well-known in the art, and which will briefly be described hereinafter. The system contains a solution of refrigerant in absorption liquid, such as ammonia in water, for example, and also an inert gas or auxiliary agent, such as hydrogen.

The generator 10 is heated in any suitable manner, as by a gas burner 14, for example, which projects its flame into lower end of a flue 15. Due to heating by burner 14 refrigerant vapor is expelled from solution in generator 10. The refrigerant vapor flows upwardly through a conduit 16 into the air-cooled condenser 11 where the vapor is condensed and flows through conduit 17 into evaporator 12.

The evaporator 12 is located in a space or compartment 18 formed by thermally insulated walls 19. Refrigerant fluid in evaporator 12 evaporates and diffuses into inert gas which enters

5 through a conduit 20, thereby producing a refrigerating effect with consequent absorption of heat from the surroundings. The rich gas mixture of refrigerant vapor and inert gas formed in evaporator 12 flows therefrom through a conduit 21, one passage of a gas heat exchanger 22, and conduit 23 into the lower part of absorber 13.

The absorber 13 is diagrammatically shown in the form of a looped coil having a plurality of 10 cooling fins 24 secured thereto for air cooling. In absorber 13 the rich gas mixture flows counter-current to downwardly flowing weak absorption liquid which enters through a conduit 25. The absorption liquid absorbs refrigerant vapor from the inert gas, and inert gas weak in refrigerant vapor flows from absorber 13 through a conduit 26, a second passage of gas heat exchanger 22, and conduit 20 into the upper part of 15 evaporator 12.

Absorption liquid enriched in refrigerant flows from the lower part of absorber 13 into an accumulation vessel 27. From vessel 27 enriched liquid flows through an inner conduit 28 of a liquid heat exchanger 29 to a coil 30 which is disposed about the lower end of flue 15. Due to heating by burner 14, liquid is raised by vapor-lift action from coil 30 through conduit 31 into the upper part of generator 10. The refrigerant vapor expelled out of solution in generator 10, together with refrigerant vapor entering through conduit 31, flows upwardly through conduit 16 into condenser 11, as explained above.

The absorption liquid from which refrigerant has been expelled flows from generator 10 through conduit 32, outer conduit 33 of liquid heat exchanger 29, and conduit 25 into the upper part of absorber 13.

The lower end of condenser 11 is connected by a conduit 34 to the gas circuit, as at gas heat exchanger 22, for example. By providing conduit 34 any non-condensable gas which passes through the condenser will flow to the gas circuit and not be trapped in the condenser.

The refrigerating effect produced by evaporator 45 or cooling element 12 of the refrigeration system is utilized to cool and liquify a volatile fluid flowing through a coil 35 which extends longitudinally within the cooling element, as shown in Fig. 2. The coil 35 constitutes the condenser of a heat transfer system embodying the invention whereby cooling may be effected at a place above the cooling element 12.

The heat transfer system includes an evaporator 36 which is of the flooded type and located 50 at a higher level than condenser 35. The evap-

orator 36 is disposed in a thermally insulated space 37 and includes a receiver 38 having a looped coil 39 connected thereto.

The condenser 35 and evaporator 36 form part of a closed fluid circuit which is partly filled with a suitable volatile liquid. The volatile liquid evaporates in evaporator 36 and takes up heat thereby producing cold. The vapor flows from evaporator 36 through a conduit 40 into condenser 35 in which the vapor is cooled and condensed by cooling element 12.

In accordance with the invention, structure including an accumulation vessel 41 is provided for raising liquid from condenser 35 to evaporator 36 so that cooling may be effected in space 37. To the lower end of condenser 35 is connected a U-shaped conduit 42 which extends below vessel 41 and is connected to the bottom thereof.

To vessel 41 is connected an overflow conduit 43 having an inverted U-shaped bend 44. In Fig. 2 the upper closed end of bend 44 is at substantially the same level as the upper part of vessel 41. From bend 44 conduit 43 extends downwardly and is connected to an intermediate part of a vaporizer 45. The vaporizer 45 constitutes a heat receiving part and is shown in heat exchange relation with the upper part of generator 10. Above the connection of conduit 43 the vaporizer 45 is connected by another conduit 46 to the upper part of vessel 41.

The operation of the heat transfer system just described is substantially as follows: Assuming that evaporator 36 is filled with liquid, vapor is formed therein and flows through conduit 40 into condenser 35 in which the vapor is cooled and condensed, as explained above. The condensed fluid flows through U-shaped conduit 42 into accumulation vessel 41. With continued evaporation of liquid in evaporator 36 and condensation of vapor in condenser 35, the liquid level will rise in vessel 41.

When the liquid level in vessel 41 rises sufficiently, liquid is siphoned by inverted U-shaped bend 44 in conduit 43 and the siphoned liquid flows into vaporizer 45. This may occur when a definite quantity of liquid has evaporated in evaporator 36, such as, for example, half of the liquid in the evaporator.

The liquid overflowing into vaporizer 45 is vaporized and the vapor formed therein flows through conduit 46 into the upper part of vessel 41. The vapor pressure continues to increase in vaporizer 45, conduit 46, and in the space above the liquid surface in vessel 41. This vapor pressure increases to a value higher than the vapor pressure above liquid in evaporator 36. When the vapor pressure above the liquid surface in vessel 41 builds up sufficiently, liquid is forced upward through conduit 42, condenser 35, and conduit 40 into receiver 38.

The heat transfer system is so constructed and arranged that sufficient liquid is siphoned from vessel 41 into vaporizer 45 before the liquid level is depressed in vessel 41 below the connection of conduit 43 thereto. The quantity of liquid siphoned into vaporizer 45 is sufficient when the vapor pressure can build up to a value to produce the necessary force to lift liquid from vessel 41 into receiver 38.

When the vapor in vessel 41 reaches the lower end of the right-hand leg of U-shaped conduit 42 during a liquid lifting period, trapped vapor will flow past liquid in the lower end of the liquid trap formed by U-shaped conduit 42. When this occurs the column of liquid in the left-hand leg

of conduit 42, condenser 35, and conduit 40 will flow back into vessel 41. The trapped vapor released into the left-hand leg of U-shaped conduit 42 is condensed in condenser 35 while the remaining vapor in vessel 41 is condensed therein. It will be apparent that vapor is formed in vaporizer 45 when the liquid rises sufficiently in vessel 41, and that this rise of liquid is recurring and constitutes a recurring condition taking place within the heat transfer system to cause intermittent flow of liquid from vessel 41 to condenser 35. Further, the heat transfer system is self-actuating and operates in accordance with a condition taking place solely within the system and independently of changes in an operating condition of the refrigerating apparatus or changes in temperature or pressure occurring outside of or external to the heat transfer system.

The periods during which liquid is raised in the system alternate with periods during which vapor is formed in evaporator 36 and condenses in condenser 35. The periods of liquid raising are relatively short compared with the periods of liquid evaporation, whereby space 37 is kept at a low temperature practically all of the time. By locating accumulation vessel in space 18 which is at a low temperature, vaporization of liquid in this vessel is prevented.

At the termination of the periods when liquid is raised to a higher level into receiver 38, the pressure in the heat transfer system becomes equalized. Since the length of time of the liquid lifting periods is relatively short, very little heat of condensation is transferred to liquid in vessel 41 by the small amount of vapor condensing therein.

In Fig. 3 is diagrammatically shown a modification of the lower part of the heat transfer system of Figs. 1 and 2. As in Fig. 2, the modification of Fig. 3 shows vessel 41 connected to a U-shaped conduit 42 which is connected at its upper end to condenser 35. The upper part of vessel 41 is connected by conduit 46 to the upper part of vaporizer 45 which is in thermal contact with the upper part of generator 10.

In place of the overflow conduit 43 having an inverted U-shaped bend 44, liquid overflows from vessel 41 in Fig. 3 over the upper peripheral edge 47 of a shallow funnel 48 which is located in any suitable manner within the upper part of the vessel. The bottom of funnel 48 is connected by a conduit 49 to an intermediate part of vaporizer 45 below the connection of conduit 46.

The operation of the heat transfer system including the modification of Fig. 3 is substantially the same as that of Fig. 2 and described above. As the liquid level rises in vessel 41 in Fig. 3, liquid overflows over the upper edge 47 of funnel 48 and flows through conduit 49 into vaporizer 45. The vapor formed in vaporizer 45 flows through conduit 46 into the upper part of vessel 41. When the vapor pressure in the upper part of vessel 41 builds up sufficiently, liquid is forced downwardly therein and through conduit 42 into evaporator 36 at the upper level.

The funnel 48 is so dimensioned that when the liquid level in vessel 41 rises to cause overflow of liquid, the overflow is relatively large whereby sufficient liquid flows into vaporizer 45 before the liquid level in vessel 41 falls below the upper edge 47 of funnel 48. The amount of liquid flowing into vaporizer 45 is sufficient, as pointed out above in connection with Fig. 2, so that the vapor pressure will build up to a value sufficient to force liquid from vessel 41 into receiver 38.

In Fig. 4 is more or less diagrammatically illustrated another modification of the heat transfer systems described above and shown in Figs. 2 and 3. The parts of the primary refrigeration system similar to those shown in Figs. 1 and 2 are designated by the same reference numerals. The evaporator 36a including receiver 38a and looped coil 39a is at a higher level than condenser 35a which is in thermal exchange relation with cooling element 12. As in the other embodiments previously described, the volatile liquid evaporates in evaporator 36a and takes up heat thereby producing cold. The vapor flows from evaporator 36a through conduit 40a into condenser 35a in which the vapor is cooled and condensed by cooling element 12.

In accordance with this modification, liquid is raised into receiver 38a by structure including an accumulation vessel 41a which is more or less in the shape of a vertical cylinder. The lower end of condenser 35a is connected by a U-shaped conduit 42a to the lower part of vessel 41a. Within vessel 41a is disposed a vertical conduit 50 having a coil 51 at the lower end thereof. The lower end of coil 51 is connected by a liquid trap 53 and conduit 52 to an intermediate part of vaporizer 45a. The vaporizer 45a at a point above the connection of conduit 52 is connected by a conduit 54 to the upper end of vertical conduit 50.

From the upper part of vessel 41a a conduit 55 extends downward and is connected at its lower end to the left-hand leg of liquid trap 53. The lower end of conduit 55 is in communication with the lower end of a conduit 56 which is also connected to the left-hand leg of trap 53 below the connection of conduit 55. The upper end of conduit 56 is connected at 57 to the lower end of conduit 40a and above condenser 35a. The conduits 42a and 56 are connected by a short oblique conduit 58.

The operation of the modification of Fig. 4 generally is the same as described above in connection with the other embodiments and differs in the manner in which liquid is raised into receiver 38a. With evaporation of liquid in evaporator 36a and condensation of the vapors in condenser 35a, the liquid level rises in accumulation vessel 41a. When the liquid level rises sufficiently in vessel 41a, liquid overflows from the left-hand leg of U-shaped conduit 42a through oblique conduit 58 and into conduit 56. The liquid overflowing into conduit 56 is conducted through liquid trap 53 and conduit 52 into vaporizer 45a.

The liquid entering vaporizer 45a is vaporized therein and the vapor flows through conduit 54 into vertical conduit 50 and coil 51. Since conduit 50 and coil 51 are surrounded by liquid which is at a considerably lower temperature than vaporizer 45a, condensation of vapor takes place in these parts. The condensate flows from coil 51 through liquid trap 53 and conduit 52 back to vaporizer 45a where it is again vaporized.

The vaporizer 45a, conduits 54 and 50, coil 51, liquid trap 53, and conduit 52 constitute a local vaporization-condensation circuit in which liquid is vaporized in vaporizer 45a and the vapors are condensed in conduit 50 and coil 51. Liquid vaporizing in vaporizer 45a takes up heat from generator 10, and the vapors condensing in conduit 50 and coil 51 gives up heat to liquid in vessel 41a.

When a liquid lifting period is started with overflow of liquid through oblique conduit 58, the vaporization-condensation circuit just described

assures sufficient liquid flowing into vaporizer 45a to effect heating of liquid in vessel 41a. With heating of liquid in vessel 41a, evaporation of liquid takes place in this vessel whereby the vapor pressure above the liquid surface builds up, thereby forcing liquid downwardly in vessel 41a and upwardly through the left-hand leg of U-shaped conduit 42a.

With liquid rising in the left-hand leg of U-shaped conduit 42a, some liquid overflows through oblique conduit 58 into conduit 56, thereby further assuring sufficient liquid being introduced into vaporizer 45a so that the vapor pressure will build up sufficiently to lift liquid into receiver 38a.

As the vapor pressure increases above the liquid surface in vessel 41a, the liquid is depressed in this vessel and also in conduit 55. At the same time the columns of liquid rise in the left-hand leg of U-shaped conduit 42a and conduit 56 until the condenser 35a and conduit 40a are filled with liquid, and liquid then flows into receiver 38a of evaporator 36a.

As the liquid level in vessel 41a falls due to raising of liquid into receiver 38a, less and less of coil 51 is immersed in liquid. With coil 51 no longer immersed in liquid or only partly immersed in liquid, the coil is no longer effectively cooled by the liquid and less and less condensation of vapors takes place therein. When condensation of vapors no longer occurs in coil 51 the generation of vapors stops in vessel 41a due to evaporation of liquid therein.

The pressure in the vaporization-condensation circuit is determined by the temperature of coil 51. When condensation of vapors does not take place in coil 51 due to the rise in temperature of this coil, the pressure in the vaporization-condensation circuit increases sufficiently so that the liquid trap formed by the lower end of coil 51 and conduit 55 is forced open. When this occurs vapor formed in vaporizer 45a can enter the upper part of vessel 41a and further lower the liquid level in this vessel until it is completely empty.

When the liquid level falls in the right-hand leg of U-shaped conduit 42a so that it is below the horizontal part of conduit 56, the liquid level will also fall in the left-hand leg of trap 53 to the same extent and vapors can enter the lower end of conduit 56. With sufficient lowering of the liquid level in the right-hand leg of conduit 42a, therefore, the liquid seal at the lower end of conduit 56 is forced open. At this time liquid is forced from trap 53 through conduit 52 into vaporizer 45a.

The vapor entering the lower end of conduit 56 will cause lifting of liquid therein so that liquid is raised in conduit 56 as well as the left-hand leg of U-shaped conduit 42a. When the lifting vapor in conduit 56 enters the lower end of conduit 40a at 57, the pressure is equalized at the upper and lower ends of the liquid column in condenser 35a and U-shaped conduit 42a. With such pressure equalization the liquid column in condenser 35a and conduit 42a falls, and the liquid returns into accumulation vessel 41a.

The vapor entering the lower end of conduit 40a through conduit 56 condenses in condenser 35a, and flow of such vapor continues until vaporizer 45a no longer contains liquid. Since conduit 56 is filled with vapor no liquid enters vaporizer 45a and the liquid lifting period terminates when vaporizer 45a is exhausted of liquid.

With liquid now raised into evaporator 36a and the pressure equalized in the heat transfer system, evaporation of liquid in evaporator 36a is resumed and condensation of this vapor is effected in condenser 35a. The condensed vapor again accumulates in vessel 41a and a liquid lifting period is again instigated when liquid overflows through oblique conduit 58 from conduit 42a into conduit 56.

Fig. 5 diagrammatically illustrates a further modification of the invention which differs from the preceding embodiments in that vapor in the heat transfer system is intermittently returned to the higher level, and, after being condensed at such higher level, may flow to one or a plurality of evaporators.

In the modification of Fig. 5 a plurality of evaporators 36b are provided at a higher level than condenser 35b of the heat transfer system. Each evaporator 36b is disposed in a separate thermally insulated space 37b and includes a receiver 38b and a looped coil 39b. An air-cooled condenser 59 is located above each space 37b and connected at its lower end by a liquid trap 60 to an upper part of a receiver 38b.

Two of the evaporators 36b are disposed one above the other with their associated air-cooled condensers 59 being connected to vertical conduit 40b. The other two evaporators 36b are also disposed one above the other with their associated condensers 59 being connected to vertical conduit 40c which branches off from the lower end of conduit 40b.

As in the previous embodiment, volatile liquid evaporates in evaporators 36b and takes up heat thereby producing cold. The vapors flow from evaporators 36b through conduits 40b and 40c into condenser 35b in which the vapors are cooled and condensed by cooling element 12 of the primary refrigeration system. The parts of the primary refrigeration system shown in Fig. 5 and similar to those shown in Fig. 1 are designated by the same reference numerals.

In Fig. 5 the structure for returning volatile fluid to the evaporators 36b at a higher level includes a first accumulation vessel 41b. The lower end of condenser 35b is connected to the upper part of vessel 41b by a U-shaped conduit 42b which also includes a second U-shaped liquid trap 61. Within vessel 41b is disposed a vertical conduit 50b having a coil 51b at the lower end thereof. The lower end of coil 51b is connected by a conduit 52b and liquid trap 53b to vaporizer 45b. The upper part of vaporizer 45b is connected by a conduit 54b to the upper end of vertical conduit 50b.

The lower part of accumulation vessel 41b is connected by a conduit 62 to the upper part of a second accumulation vessel 63. The lower part of vessel 63 is connected by a conduit 64 to the lower end of a vaporizer 65. The vaporizer 65 may be heated in any suitable manner, and, as shown in Fig. 5, is arranged to be heated by heat rejected by absorber 13b.

The absorber 13b may be connected in the primary refrigeration system in the manner illustrated in Fig. 1 and is diagrammatically shown as a looped coil. The vaporizer 65 is also diagrammatically shown as a looped coil extending through absorber 13b. The absorber 13b is provided with cooling fins 24b for air cooling.

The upper end of vaporizer 65 is connected by a vertical conduit 66 to the lower end of conduit 40b. This connection at 67 is above the upper end of condenser 35b of the heat transfer

system. The conduit 66 is in heat exchange relation with the left-hand leg of U-shaped conduit 42b.

The upper part of the accumulation vessel 63 is connected by a conduit 68 to the lower end of conduit 40b and above the condenser 35b. The upper part of vessel 41b is connected by a conduit 55b to conduit 52b. At the point where the lower end of coil 51b is connected to conduit 52b the latter joins the lower end of conduit 56b. The upper end of conduit 56b is connected at 69 to the upper part of vertical conduit 66 and above the region where it is in heat exchange relation with the left-hand leg of U-shaped conduit 42b.

When the evaporators 36b are filled with liquid, evaporation of volatile fluid takes place therein and condensation of the vapors is effected in condenser 35b. The condensate flows from condenser 35b through liquid trap 61 and U-shaped conduit 42b into the upper part of accumulation vessel 41b. When the liquid level in vessel 41b reaches the upper connection of conduit 55b, liquid overflows through this conduit and thence through conduit 52b and liquid trap 53b into vaporizer 45b.

The liquid entering vaporizer 45b is vaporized therein and the vapors flow through conduit 54b into vertical conduit 50b and coil 51b. As in the modification of Fig. 4, condensation of vapors takes place in these parts thereby giving up heat to liquid in vessel 41b. The condensate flows from coil 51b and returns to vaporizer 45b through conduit 52b and liquid trap 53b. With heating of liquid in vessel 41b liquid evaporates and the vapor pressure above the liquid surface builds up. With increase in such vapor pressure liquid is forced downwardly in vessel 41b and upwardly through conduit 62 into the upper part of the second accumulation vessel 63 which is located outside the thermally insulated space 18.

Liquid flows from vessel 63 through conduit 64 into vaporizer 65. In vaporizer 65 liquid is vaporized by heat rejected from absorber 13b of the primary refrigeration system. The heating effected by absorber 13b results from the heat liberated with absorption of refrigerant vapor into absorption liquid in the primary refrigeration system. The vapor formed in vaporizer 65 flows upwardly through conduit 66 and through conduits 40b and 40c into the several condensers 59 in which it is condensed. The condensate flows from the condensers through liquid trap 60 into the receivers 38b of evaporators 36b.

By providing the additional liquid trap 61 in U-shaped conduit 42b and arranging the left-hand leg of the latter in heat exchange relation with conduit 66, condenser 35b is filled with liquid during the periods when vaporized fluid is being returned to the higher level. Due to thermal contact between conduit 66 and the left-hand leg of U-shaped conduit 42b, liquid in the latter is heated and the pressure in this leg becomes approximately the same as the vapor pressure in vessel 41b. The pressure in the left-hand leg of U-shaped conduit 42b acts on liquid in the left-hand leg of liquid trap 61 and is effective to keep condenser 35b filled with condensate or liquid. By keeping condenser 35b filled with liquid, this condenser is rendered inoperative and condensation of vapors is effected in condensers 59.

During the above described portion of the operation, the liquid level falls in vessel 41b due to forcing of liquid into vessel 63. As in the modification of Fig. 4, less and less of coil 51b is immersed in liquid with lowering of the liquid level,

whereby less and less condensation of vapors takes place in the coil. This results in an increase in the pressure existing in the vaporization-condensation circuit, and, when this pressure increases sufficiently, the liquid trap formed by the lower end of coil 51b, conduit 52b, and conduit 55b is forced open. When this occurs vapors in coil 51b can flow through conduit 55b into the upper part of vessel 41b. With the forcing open of this liquid trap, liquid rises in conduit 56b. The vapor pressure in vessel 41b now becomes sufficiently great to force the remaining liquid in this vessel through conduit 62 into vessel 63.

With all of the liquid removed from vessel 41b a path of flow is provided for the vapors through conduit 62 into accumulation vessel 63. The vapor entering vessel 63 through conduit 62 is conducted through conduit 68 into the lower end of conduit 40b. When this occurs the liquid in condenser 35b falls and flows into vessel 41b. This renders condenser 35b operative again and vapor flowing upward in conduit 66 is now condensed in the condenser. Liquid in conduit 56b flows into vaporizer 45b and vaporizes therein. This vapor is condensed in condenser 35b and returns to accumulation vessel 41b.

With vaporizer 68 no longer containing liquid and vaporizer 45b also being empty, the period for returning vaporized fluid to the evaporators is terminated, and, since condenser 35b is again operative to condense vapor in the heat transfer system, evaporation of liquid is resumed in evaporators 36b. The pressure in the heat transfer system is now equalized, the pressure being determined by the low temperature of condenser 35b.

In Fig. 6 is diagrammatically illustrated another manner of connecting a plurality of evaporators in a heat transfer system of the character shown in Fig. 5 and just described. In place of a number of condensers each connected to a separate evaporator, as shown in Fig. 5, a single condenser 59a is employed in Fig. 6. The upper end of condenser 59a is connected by a vertical conduit 40d to the upper end of the condenser of the heat transfer system, as in the modification of Fig. 5. The lower end of condenser 59a is connected by a conduit 70 to a horizontal conduit 71 to which is connected a first group of evaporators 36c. The evaporators 36c are of the flooded type and include a receiver 38c and a looped coil 39c. The lower end of conduit 70 is provided with a liquid trap 72 which is connected by a vertical conduit 73 to another horizontal conduit 74 to which is connected a second group of evaporators 36c. The lower end of conduit 73 is provided with a liquid trap 75 which is connected by a conduit 76 to a horizontal conduit 77 having a third group of evaporators 36c connected thereto.

A liquid trap 78 at the lower end of conduit 76 is connected by a conduit 79 to a horizontal conduit 80 having a fourth group of evaporators 36c connected thereto. The upper parts of liquid traps 72, 75, and 78 are connected by conduits 81, 82, and 83, respectively, to vertical conduit 40d. The lower end of conduit 78 is also connected to conduit 40d by a conduit 84.

When the condenser of the heat transfer system is filled with liquid and rendered inoperative, vaporous volatile fluid will flow upwardly in conduit 40d, as explained above in connection with the modification of Fig. 5. During this period of the operation of the system, condensation of vapors takes place in condenser 59a.

The condensate formed in condenser 59a flows

5 through conduit 74 into horizontal conduit 71 and fills up the evaporators 36c at the highest level. When these evaporators are filled with liquid, liquid overflows from trap 72 into vertical conduit 73 whereby the evaporators connected to conduit 74 are next filled with liquid. In this manner each group of evaporators is filled with liquid until liquid flows into the evaporators 36c at the lowest level.

When the condenser of the heat transfer system is no longer filled with liquid and again rendered operative, evaporation of liquid takes place in the evaporators 36c. The vapors formed in evaporators 36c flow through conduits 81, 82, 83, and 84 into vertical conduit 40d, and thence into the condenser of the heat transfer system. The vapors are condensed in the condenser and the liquid condensate flows into an accumulation vessel, as in the modification of Fig. 5, until sufficient liquid is accumulated whereby volatile fluid is again returned to the evaporators at the higher level.

25 The heat transfer systems of Figs. 2, 3, and 4 may be provided with a plurality of evaporators connected in series or parallel or in any other suitable manner. The evaporators may be arranged in the same manner as shown in Fig. 6, for example, with a collection vessel employed in place of the condenser 59a.

20 The several groups of evaporators in Fig. 6 may be located in different floors of a building. The modifications of Figs. 5 and 6 possess an advantage over the systems of Figs. 2, 3, and 4 where volatile fluid is returned from a lower level through a relatively great height to one or a plurality of evaporators at a higher level. In Figs. 2, 3, and 4 liquid in the riser conduits returns to the accumulation vessel at the end of a liquid lifting period. Such return flow of liquid is avoided in the heat transfer systems of Figs. 5 and 6.

45 While several embodiments of the invention have been shown and described, such variations and modifications are contemplated as fall within the true spirit and scope of the invention, as pointed out in the following claims.

What is claimed is:

1. A method of heat transfer which includes simultaneously vaporizing liquid at a place of evaporation at an upper elevation and condensing vaporized fluid in a place of condensation at a lower elevation, collecting condensate at a place of accumulation, and intermittently stopping such vaporization of liquid and condensation of fluid and raising liquid condensate to said place of evaporation by trapping vapor above a surface level of accumulated condensate to exert force thereon, and thereafter releasing such trapped vapor to said place of condensation to terminate the raising of liquid condensate to said place of evaporation.

50 2. A method of heat transfer which includes vaporizing liquid in a place of evaporation at an upper elevation, condensing vaporized fluid in a place of condensation at a lower elevation, collecting condensate in a place of accumulation, stopping such vaporization of liquid and condensation of fluid and raising liquid condensate to said place of evaporation by trapping vapor above a surface level of condensate to exert force thereon, forming such trapped vapor by conducting condensate to a place of vaporization below the place of accumulation, and terminating the raising of liquid condensate to said place of evaporation and resuming vaporization of liquid and

condensation of fluid in said places of evaporation and condensation, respectively, by releasing such trapped vapor to said place of condensation.

3. A method of heat transfer which includes simultaneously vaporizing liquid in a place of evaporation at an upper level and condensing vaporized fluid in a first place of condensation at a lower level, intermittently vaporizing condensate in a place of vaporization, flowing such vaporized condensate into a second place of condensation at a level above the place of vaporization, conducting liquid from the second place of condensation into the place of evaporation, and permitting condensation of vaporized condensate in the second place of condensation by filling the first place of condensation with liquid so that vaporized fluid will not be condensed therein.

4. A method of heat transfer which includes simultaneously vaporizing liquid in a first place of vaporization at an upper elevation and condensing vaporized fluid in a place of condensation at a lower elevation, intermittently stopping such vaporization of liquid and condensation of fluid and raising condensate between said elevations by conducting condensate to a place of accumulation, conducting condensate to a second place of vaporization when a predetermined quantity of condensate has accumulated at the place of accumulation, trapping vapor formed at the second place of vaporization above a surface level of liquid condensate in the place of accumulation to exert force thereon to raise condensate between said elevations, and subsequently releasing the trapped vapor to the place of condensation to terminate the raising of condensate between said elevations.

5. A method of heat transfer which includes simultaneously vaporizing liquid in a place of evaporation at an upper elevation and condensing vaporized fluid in a place of condensation at a lower elevation, conducting liquid from the place of condensation to a place of accumulation, intermittently stopping such vaporization of liquid and condensation of fluid and raising liquid between said elevations and through the place of condensation by trapping vapor above a surface level of liquid in the place of accumulation to exert force thereon, and terminating such raising of liquid by releasing trapped vapor to the place of condensation.

6. A method of heat transfer which includes simultaneously vaporizing volatile liquid in a place of evaporation at an upper elevation and condensing vaporized fluid in a place of condensation at a lower elevation, conducting liquid condensate from the place of condensation to a place of accumulation, intermittently stopping such vaporization of liquid and condensation of fluid and raising liquid to the place of evaporation by trapping vapor above a surface level of liquid in the place of accumulation to exert force thereon and subsequently releasing such trapped vapor to said place of condensation to terminate the raising of liquid to the place of evaporation, and heating liquid in the place of accumulation to form the trapped vapor.

7. In the art of heat transfer in which volatile liquid is vaporized in a place of evaporation and vaporized fluid is condensed in a place of condensation, such vaporization of liquid and condensation of vaporized fluid being effected at substantially the same pressure, the improvement which consists in collecting liquid condensate in a place of accumulation, and returning liquid from the place of accumulation to the

place of evaporation and stopping the vaporization of liquid and condensation of fluid in the places of evaporation and condensation, respectively, by keeping the place of condensation filled with liquid.

5 8. In the art of heat transfer in which volatile liquid is vaporized in a place of evaporation and vaporized fluid is condensed in a place of condensation, the improvement which consists in stopping such vaporization of liquid and condensation of fluid and returning liquid to the place of evaporation by collecting liquid condensate in a place of accumulation, flowing liquid from the place of accumulation to a place of vaporization, trapping vapor formed in the place of vaporization above a surface level of liquid at the place of accumulation to exert force thereon to cause fall of liquid level, and subsequently releasing the trapped vapor from the place of accumulation to stop the return of liquid to the place of evaporation and to allow liquid condensate to collect again in the place of accumulation.

10 9. In the art of heat transfer in which liquid is vaporized in a place of evaporation and vaporized fluid is condensed in a place of condensation, the improvement which consists in returning liquid to the place of evaporation by collecting liquid condensate in a place of accumulation, intermittently siphoning liquid from the place of accumulation to a place of vaporization, and trapping vapor formed in the place of vaporization above a surface level of liquid at the place of accumulation to exert force thereon to cause fall of liquid level, and subsequently releasing the trapped vapor from said place of accumulation to permit rise of liquid level in the place of accumulation.

15 10. Refrigeration apparatus including a heat receiving part and a cooling element, a heat transfer circuit partly filled with a volatile liquid and including an evaporator in which liquid is vaporized and a condenser in which vapors are condensed, said condenser being in heat exchange relation with said cooling element, a vessel connected to receive condensate from said condenser, means associated with said circuit to return condensate from said vessel through said condenser to said evaporator and including a member in thermal exchange relation with said heat receiving part, and a heater for heating said part.

20 11. A heat transfer system including a circuit partly filled with a volatile liquid and including an evaporator in which liquid is vaporized and a first condenser in which vaporized fluid is condensed, an accumulator connected to receive liquid from said first condenser, and structure to return liquid from said accumulator to said evaporator including a vaporizer into which liquid is conducted from said accumulator, a second condenser above said evaporator connected to receive vaporized fluid formed in said vaporizer, said second condenser being connected to conduct liquid to said evaporator, and means to prevent liquid from flowing from said first condenser to said accumulator while liquid is vaporizing in said vaporizer and vaporized fluid is condensing in said second condenser.

25 12. A method of transferring heat which includes vaporizing liquid in a place of vaporization, flowing to a place of condensation substantially all of the vaporized fluid formed in the place of vaporization, condensing the vaporized fluid in the place of condensation, flowing condensate by gravity from said place of condensation to a place of accumulation, and vaporizing

a part of said condensate to cause flow of liquid from the place of accumulation through the place of condensation to the place of vaporization.

13. In the art of transferring heat with the aid of a system having a place of vaporization in which liquid is vaporized and a place of condensation connected to receive substantially all of the vaporized fluid formed in the place of vaporization and in which the vaporized fluid is condensed, the improvement which consists in flowing condensate by gravity from the place of condensation to a place of accumulation, and utilizing vapor in the system to cause condensate to flow from the place of accumulation through the place of condensation to the place of vaporization.

14. In a heat transfer system including a circuit for heat transfer fluid having an evaporator at an upper elevation in which fluid is vaporized and a condenser at a lower elevation in which is liquefied substantially all of the vaporized fluid formed in the evaporator, a vessel for accumulating liquid below the condenser, a conduit from the lower part of said vessel to the evaporator at the upper elevation, said conduit including the condenser, and means for intermittently trapping vapor above the surface level of liquid in said vessel to cause alternate upward flow of liquid in said conduit from said vessel and downward flow of condensate from the condenser into said vessel.

15. A method of heat transfer which includes simultaneously vaporizing volatile liquid in a place of evaporation and condensing vaporized fluid in a place of condensation, flowing liquid condensate from the place of condensation to a place of accumulation in a path of flow which always provides for unrestricted flow of liquid therethrough, and intermittently returning liquid to said place of evaporation by first trapping vapor above a surface level of accumulated liquid condensate to exert force thereon and, subsequently releasing such trapped vapor to said place of condensation, the trapped vapor being segregated by liquid condensate from said place of condensation before being released thereto.

16. A method of heat transfer which includes vaporizing volatile liquid in a place of evaporation, condensing vaporized fluid in a place of condensation, flowing liquid condensate from the place of condensation to a place of accumulation in a path of flow which always provides for unrestricted flow of liquid therethrough, and intermittently returning liquid to the place of evaporation by trapping vapor above a surface level of condensate to exert force thereon, forming such trapped vapor by conducting condensate to a place of vaporization in communication with the place of accumulation, and releasing the trapped vapor to the place of condensation after returning liquid to the place of evaporation, the trapped vapor being segregated by liquid from the place of condensation before being released thereto.

17. A method of heat transfer which includes simultaneously vaporizing volatile liquid in a first place of vaporization and condensing vaporized fluid in a place of condensation, intermittently returning condensate to the first place of vaporization by conducting liquid condensate from the place of condensation to a place of accumulation in a path of flow which always provides for unrestricted flow of liquid therethrough, conducting condensate to a second place of vaporization

when a predetermined quantity of condensate has accumulated in the place of accumulation, trapping vapor formed in the second place of vaporization above a surface level of liquid condensate at the place of accumulation to exert force thereon to return condensate to the first place of vaporization, and subsequently releasing the trapped vapor to the place of condensation.

18. In a method of transferring heat with the aid of a system in which all places are always in unobstructed fluid communication with each other and in which heat is transferred by vaporizing liquid at a high temperature place of vaporization, flowing vapor from such place of vaporization to a place of condensation where heat is rejected, and condensing vapor at the place of condensation, steps of supplying a limited quantity of liquid to said place of vaporization, forcing condensate to a lower temperature place of vaporization upon increase in pressure in said high temperature place of vaporization resulting from vaporization of liquid therein, flowing vapor from the lower temperature place of vaporization to the place of condensation after the high temperature place of vaporization is depleted of liquid, condensing the last mentioned vapor and withholding the liquid condensate from both the high and lower temperature places of vaporization, and again supplying a limited quantity of liquid to the high temperature place of vaporization upon increase in liquid level of the withheld condensate.

19. A heat transfer system comprising a vaporization-condensation circuit partly filled with a volatile liquid and including low and higher temperature evaporation members and a condensation member, liquid holding means in said circuit to withhold liquid condensate from both of said evaporation members and operative to supply a quantity of liquid to said higher temperature evaporation member upon rise in liquid level in said liquid holding means, and said low temperature evaporation member being connected to receive liquid from said liquid holding means in a path of flow including said condensation member upon increase in pressure in said higher temperature evaporation member resulting from evaporation of liquid therein.

20. A vaporization-condensation heat transfer circuit containing a volatile fluid and having two portions in fluid communication each provided with a vaporization part, said circuit including a condensation part for condensing therein vaporized fluid formed in both of said vaporization parts, and structure for causing fluid in liquid phase to flow alternately to said portions, said structure being so constructed and arranged that when liquid flows to one of said portions such liquid passes through the condensation part of said heat transfer circuit.

21. In a heat transfer system comprising a vaporization-condensation circuit partly filled with a volatile liquid, said circuit including a first evaporation member and a condensation member forming a first portion and a second evaporation member and said condensation member forming a second portion in fluid communication with said first portion, said condensation member being capable of condensing therein vaporized fluid formed in said first and second vaporization members, and structures embodied in said circuit for causing flow of liquid alternately to said portions, said structure being so constructed and arranged that liquid flowing to one of said portions passes through said condensation member.

22. A method of heat transfer which includes simultaneously vaporizing volatile liquid in a place of evaporation and condensing vaporized fluid in a place of condensation, conducting liquid condensate from the place of condensation to a place of accumulation, intermittently stopping such vaporization of liquid and condensation of fluid and returning liquid to the place of evaporation by trapping vapor above a surface level of liquid in the place of accumulation to exert force thereon and subsequently releasing such trapped vapor to said place of condensation, and forming the trapped vapor in the place of accumulation by heating liquid therein by heat derived from vapors formed in a place of vaporization to which liquid condensate is conducted.

23. In the art of heat transfer in which volatile liquid is vaporized in a place of evaporation and vaporized fluid is condensed in a place of condensation, the improvement which consists in stopping such vaporization of liquid and condensation of fluid and returning liquid to the place of evaporation by collecting liquid condensate in a place of accumulation, flowing liquid from the place of accumulation to a place of vaporization, trapping vapor formed in the place of vaporization above the surface level of liquid at the place of accumulation to exert force thereon to cause fall of liquid level, and stopping the flow of liquid from the place of accumulation to the place of vaporization after the liquid level in the place of accumulation is depressed to a predetermined level by the trapped vapor.

24. Refrigeration apparatus including a heat transfer circuit partly filled with a volatile liquid and comprising a plurality of parts including an evaporator in which liquid is vaporized and a condenser connected to receive vaporized fluid from said evaporator and disposed below the latter, and a cooling element in heat exchange relation with said condenser to render the latter capable of liquefying vaporized fluid formed in said evaporator, said circuit being so constructed and arranged that said condenser is intermittently rendered ineffective to liquefy vaporized fluid formed in said evaporator and volatile liquid is introduced into said evaporator responsive to accumulation of liquid in one of said parts of said circuit.

25. A heat transfer system including a circuit partly filled with a volatile liquid and comprising a plurality of parts including an evaporator in which liquid is vaporized and a condenser connected to said evaporator and in which normally is liquefied substantially all of the vaporized fluid formed in the latter, such vaporization of liquid in said evaporator and condensation of vaporized fluid in said condenser being effected at substantially the same pressure determined by the temperature of said condenser, said circuit being so constructed and arranged that said condenser is intermittently rendered ineffective and volatile liquid formed in said condenser is returned to

said evaporator responsive to accumulation of liquid in one of said parts of said circuit and while said evaporator is partly filled with liquid.

26. Refrigeration apparatus including a heat transfer circuit partly filled with a volatile liquid and comprising a plurality of parts including an evaporator in which liquid is vaporized, a condenser connected to receive vaporized fluid from said evaporator, an accumulator, and a connection for draining liquid condensate from said condenser to said accumulator, a cooling element in heat exchange relation with said condenser to render the latter capable of liquefying vaporized fluid formed in said evaporator, said condenser and said accumulator always being in unobstructed fluid communication with each other through said connection, and said circuit being so constructed and arranged that volatile liquid is returned intermittently from said accumulator to said evaporator responsive to accumulation of liquid in said accumulator.

27. A heat transfer system including a circuit partly filled with a volatile liquid and comprising a plurality of parts including an evaporator in which liquid is vaporized and a condenser connected to said evaporator and in which normally is liquefied substantially all of the vaporized fluid formed in the latter, such vaporization of liquid in said evaporator and condensation of vaporized fluid in said condenser being effected at substantially the same pressure determined by the temperature of said condenser, said circuit being so constructed and arranged that said condenser is intermittently rendered ineffective to cause the pressure in said circuit to increase sufficiently to stop vaporization of volatile liquid in said evaporator responsive to accumulation of liquid in one of said parts in said circuit, the arrangement and construction of said circuit further being such that when said condenser is rendered ineffective volatile liquid is introduced into said evaporator.

28. A heat transfer system partly filled with a volatile liquid and comprising a plurality of parts all of which are in unobstructed fluid communication, said parts including a vaporizer in which liquid is vaporized and a condenser connected to said vaporizer and in which normally is liquefied substantially all of the vaporized fluid formed in the latter, the heat resulting from liquefaction of vaporized fluid in said condenser being rejected to a medium in thermal conductive relation therewith, said circuit being so constructed and arranged that only intermittent flow of fluid from said vaporizer to said condenser is effected during operation of the system responsive to accumulation of liquid in one of said parts of said circuit, and the arrangement and construction of said circuit further being such that intermittent flow of fluid from said vaporizer to said condenser is effected even when said vaporizer is partly filled with liquid.

ERIK SIGFRID LYNGER.
